UNITED STATES PATENT OFFICE.

ROBERT L. TUDOR, OF BUFFALO, NEW YORK.

BOX-COVER LIFTER.

No. 874,043.

Specification of Letters Patent.

Patented Dec. 17, 1907.

Application filed December 17, 1906. Serial No. 348,364.

To all whom it may concern:

Be it known that I, ROBERT L. TUDOR, a citizen of the United States, residing at Buffalo, in the county of Erie and State of New York, have invented a new and useful Improvement in Box-Cover Lifters, of which the following is a specification.

The object of this invention is to provide a simple, effective and inexpensive lifter for 10 the covers of boxes in which shoe polish or other material is packed.

In the accompanying drawings: Figure 1 is a side elevation of a box for holding shoe polish or the like having its cover closed and 15 provided with my improved cover lifter. Fig. 2 is a similar view showing the cover of the box lifted on one side by my improved lifter preparatory to being wholly removed therefrom. Fig. 3 is a horizontal section in line 20 3-3, Fig. 1. Fig. 4 is a vertical cross section in line 4-4, Fig. 1. Figs. 5 and 6 are fragmentary sectional views, on an enlarged scale, of the joint between the box and cover and the lifting device applied, showing different 25 positions of the same. Fig. 7 is a fragmentary vertical section showing my invention applied to a box having a slightly different bead from that shown in Figs. 4 and 6.

Similar letters of reference indicate corresponding parts throughout the several views.

Although my invention is applicable to various forms of boxes, that shown in the drawings, as an example, is constructed of tin in round form and consists of a lower part 35 or body A and an upper part or cover B which fits with its marginal flange b around the marginal flange a of the body. At a distance from the edge of the body the flange of the latter is provided with an external annular bead or rib C with which the edge of the flange on the cover engages and forms a stop for limiting the movement of the cover on the body upon closing the same.

D represents a rotary cam or eccentric 45 pivoted by means of a rivet e on the flange of the cover so as to turn in a plane parallel with the side of the box. In the closed position of the cam, its low or receding part is arranged directly between the pivot of the cam 50 and the bead C, as shown in Figs. 1 and 4. Upon turning the cam in the direction for engaging its high or salient part with the bead directly opposite the pivot thereof, the cover will be lifted from the body on the respective 55 side of the box, as shown in Figs. 2 and 6, by

the wedge action of the cam against the bead.

In order to enable the cam to reliably engage the bead in all positions of its turning movement, the cam is normally curved in 60 the direction of its major axis so that it is concentric with the body of the box in the inoperative position of the cam, as shown in Fig. 3. As the cam is turned from its inoperative position, shown in Figs. 1 and 5 to 65 its operative position shown in Figs. 2 and 6, its outermost or free end is deflected upon riding over the swell or peripheral part of the box lying between the pivot e and the inwardly turned extremity of the cam. The 70 resilience of the cam causes the free or salient end of the same upon swinging below the cover flange to project inwardly underneath the same and bear against the bead close to the flange of the box, thereby 75 reducing the tendency of the cam to slip off from the flange and rendering the opening of the cover more reliable.

In order to positively prevent the cam from slipping off from the bead and enable 80 the same to obtain a firm and reliable bearing on the same, the upper side of this bead is so constructed as to form an annular channel or groove f thereon. When turning the cam, its operative edge or periphery enters 85 this groove and is confined against lateral movement relatively to the body, thus preventing slippage of the cam from said bead and always insuring an effective action of the same for lifting the cover from the body. 90 Inasmuch as the bead having the annular groove extends all the way around the body, it is immaterial what the position of the cover is, circumferentially, relatively to the body in applying the cover thereto, because 95 in all positions of the cover the cam is opposed by some portion of the bead and the latter serves as an abutment which receives the thrust of the cam for opening the cover. Instead of providing the upper side of the 100 bead with a groove for the reception of the periphery of the cam, said bead may be flat on its upper side, as shown at f' in Fig. 7, so as to present an abutment from which the cam will not slip off as it would from a bead 105 having a rounded upper side.

Various means may be provided for turning the cam but preferably that shown in the drawings which consists of a handle or thumb piece g arranged at the upper edge of 110

the cam and projecting outwardly therefrom, as shown in Figs. 1 and 4. The cam and its thumb piece are preferably stamped out of a single piece of sheet metal.

5 My improved cover lifter is exceedingly simple in construction, its action is absolutely reliable, its cost is very small and its application to the box does not require any material departure from the standard type 10 now in common use.

I claim as my invention:

1. The combination of a box body having a circular side wall or flange, a box cover having a circular side wall or flange which 15 fits over the edge of said body wall, an annular bead arranged on the outer side of the body wall and having a groove in its upper side, and a cam or eccentric pivoted on the cover wall and engaging with the groove of 20 said bead, substantially as set forth.

2. The combination of a box body having its wall or flange provided with an annular bead, a cover fitting with its wall or flange over the wall of the body, and a cam or ec- 25 centric pivoted transversely on the wall of

the cover and engaging its periphery with said bead and curved concentrically with the wall of the cover in the inoperative position of the cam or eccentric, substantially as set forth.

30

3. The combination of a box body having a circular side wall or flange, a box cover having a circular side wall or flange which fits over the edge of said body wall, an annular bead arranged on the outer side of the 35 body wall and having a groove in its upper side, and a cam or eccentric pivoted transversely to the wall of the cover and engaging its periphery in the groove of said bead and normally curved in the direction of its major axis so that in its inoperative position the same is concentric with the wall of the cover, substantially as set forth.

Witness my hand this 11th day of December, 1906.

ROBERT L. TUDOR.
